CLAIM

The ornamental design for a cash box with coin tray, as shown and described.

DESCRIPTION

FIG. 1 is a top view of a cash box with coin tray, showing our new design shown in a closed position;

FIG. 2 is another top view of FIG. 1, with the coin tray and cash box shown in an open position;

FIG. 3 is another top view of FIG. 1, with the coin tray shown in a closed position and the cash box shown in an open position;

FIG. 4 is a left side view of FIG. 2;

FIG. 5 is a right side view of FIG. 2;

FIG. 6 is a bottom view of FIG. 2;

FIG. 7 is a front view of FIG. 2;

FIG. 8 is a back view of FIG. 2;

FIG. 9 is a front perspective view of FIG. 2; and,

FIG. 10 is a front perspective view of FIG. 3.

The even dashed broken lines depict portions of the cash box with coin tray that form no part of the claimed design.
